STERILE PACKAGE

Michael S. Burnhill, Brooklyn, N.Y., assignor to American
Cadeuceus Industries, Inc., New York, N.Y.

Filed Aug. 10, 1970, Ser. No. 24,390

Term of patent 14 years

Int. Cl. D24—02; D9—04
U.S. Cl. D83—1

FIG. 1

FIG. 2

FIG. 3

FIG. 4

FIG. 5

FIG. 6

FIG. 1 is a front perspective view of the design for a sterile package with its cover in partially removed position;

FIG. 2 is a top plan view thereof with the cover removed;

FIG. 3 is a front view thereof with the cover removed;

FIG. 4 is a left side view thereof with the cover removed;

FIG. 5 is a bottom plan view thereof with the cover removed; and

FIG. 6 is a top perspective view thereof with the sterile seal rolled back from the top thereof.

The broken lines are shown for illustrative purposes only and do not form a part of the claimed design.

I claim:

The ornamental design for a sterile package, as shown and described.
